SUPPORTING STRUCTURE FOR A PLURALITY OF ROLLS

Lionel G. Lindsay, Los Angeles, Calif.

Application April 21, 1947, Serial No. 742,958

13 Claims. (Cl. 242—64)

1

This invention relates to a structure for supporting rolls, such, for example, as rolls of photographically sensitive paper.

Photographic printing machines, such as blue print machines or "Ozalid" printing machines, are usually supplied with sensitized paper from a roll located adjacent the feeding end of the machine.

It is one of the objects of this invention to make it possible to replace an exhausted roll in a very simple manner, and without the necessity of leaving the machine idle for any appreciable period.

It is another object of this invention to provide a device of this character that may be very easily loaded with rolls for successive use; and while the machine is in active operation, a roll may be placed into position so that it may be moved into operative position as soon as the current roll is exhausted.

It is still another object of this invention to provide a structure of this character that can preclude the fogging of the paper on the rolls, by the aid of substantially light proof chambers in which the rolls are accommodated.

This invention possesses many other advantages, and has other objects which may be made more clearly apparent from a consideration of several embodiments of the invention. For this purpose there are shown a few forms in the drawings accompanying and forming a part of the present specification. The forms will now be described in detail illustrating the general principles of the invention; but it is to be understood that this detailed description is not to be taken in a limiting sense, since the scope of this invention is best defined by the appended claims.

Referring to the drawings:

Figure 1 is a side elevation of a structure embodying the invention;

Figs. 2, 3, and 4 are enlarged sectional views, taken respectively along planes corresponding to lines 2—2, 3—3, and 4—4 of Fig. 1;

Fig. 5 is a side elevation of a modified form of the invention;

Fig. 6 is a sectional view, taken substantially along a plane corresponding to line 6—6 of Fig. 5;

Fig. 7 is a sectional view, taken along a plane corresponding to line 7—7 of Fig. 6;

Fig. 8 is a fragmentary view, partly broken away, illustrating an element of the apparatus illustrated in Figs. 5 and 6; and

Fig. 9 is an enlarged sectional view, taken along a plane corresponding to line 9—9 of Fig. 6.

2

In Figs. 1 and 2 a table 1 is illustrated having a rounded front edge 2. This table 1 is intended to provide a support for sensitized paper 3 to be fed to a printing machine adjacent the table 1.

The paper 3 is shown as being supplied from a roll 4 supported underneath the table 1. For this purpose the roll 4 is mounted on a cylindrical rod 5. This rod 5, in turn, is supported by the aid of a frame structure. This frame structure has two side plates 6 and 7, between which the rod 5 extends. A supplemental rod 8, similar to rod 5, is also disposed between the plates 6 and 7. It is intended to support a supplemental roll 9. Thus, by reversal of the frame structure, the roll 9 may be brought into the operative position of roll 4.

In order that the frame structure may thus be reversed in position, it is pivotally mounted, as by the aid of a shaft 10 that passes through the plates 6 and 7 and is rigidly attached thereto. The shaft 10 is supported at its ends in appropriate standards 11 mounted on brackets 12. These brackets 12 are fastened to the lower side of the table 1.

The frame member including plates 6 and 7, and shaft 10 may be rotated in a clockwise direction, as viewed in Fig. 1, about the axis of shaft 10, and a latch mechanism is provided to hold this frame structure in its angularly adjusted position. Thus, extending transversely from the bracket 12 is a strap 13 (Figs. 1 and 4).

A standard 14 is attached to the strap 13 and serves to pivot a pair of hook members or latches 15 and 16. Hook member 15 has a sloping surface 18 adapted to be contacted by the frame plate 7 in its rotational movement and to depress the hook member 15 against the force of a compression spring 19.

The plate 7 proceeds until it passes beyond the sloping surface 18 and then the abrupt abutting surface 20 of hook 15 engages the plate. It is held against this abutting surface by the manually operable hook member 16. This hook member 16 forms an abutment for the right-hand side of the plate 7. It may be released, as by the aid of a knob 22 having a stem 23 pivotally joined to the hook 16. A compression spring 24 urges the hook 16 into operative position.

Accordingly, when the plate 7 moves in a clockwise direction, and with the knob 22 in the normal position, the hook 15 will be depressed and the plate 7 will move to the full-line position of Fig. 4. It will be held there between the two hooks 15 and 16.

When it is desired to rotate the frame formed by the members 6, 7, and 10, the knob 22 is pulled and the plate member 7 can be moved away from it, thus freeing the frame structure.

The roll supporting rods 5 and 8 are arranged to be readily disengageable from the plates 6 and 7 for the purpose of placing new rolls thereon. Thus, for example, in the position of Fig. 1, the lower rod 8 can be loaded with a roll 9 while the machine is in operation.

Since the mechanisms associated with rods 5 and 7 are identical, it is necessary to describe only one of them.

Thus, rod 5 is slidably mounted in the frame 6 and is provided with a head 25 which abuts the left hand side of the plate 6. A compression spring 26, abutting the collar 27 mounted on the rod 5, serves to urge rod 5 toward the right. The aperture in plate 6 through which rod 5 passes is provided with tapered portions 6a on each side of the plate 6, as indicated in connection with rod 8 in Fig. 2. In this way, when the right-hand end of rod 5 is free, the rod 5 can be moved universally with respect to this aperture.

The right-hand end of the rod 5, as shown most clearly in Fig. 3, is receivable in an aperture 28 formed in a wall 29. This wall 29 is attached, as by welding, to the plate member 7. It has a sloping surface 30 inclined to the axis of rod 5. The aperture 28 is at the bottom of the slope. The wall 29 forms the bottom of a slot or recess 31 into which the end of the rod 5 projects. As the rod 5 is placed into the slot, its end slides on the surface 30 and spring 26 is slightly compressed. When the rod 5 reaches the full-line position of Fig. 3, spring 26 urges it into the aperture 28. It is restrained against removal by the edge of this aperture.

To remove the rod 5, it may be pulled toward the left, as viewed in Fig. 2, compressing spring 26. Then, as the end of the rod 5 is freed from the aperture 28, it may be moved outwardly for removing an exhausted roll and for replacing a new roll.

When the paper to be supplied is quite sensitive to light, it is necessary to provide enclosures that would prevent the paper from fogging. Such paper is often used in special types of printing, such as "Ozalid" printing.

An arrangement for providing such an enclosure is illustrated in Figs. 5, 6, 7, 8, and 9.

In this form of the invention, the table 32 which is adjacent the feeding end of the printing machine serves to support brackets 33 and 34. These brackets provided bearings having a central shaft 35 upon which are mounted the end frames 36 and 37. Frame 36 is shown in this instance as provided with four equiangularly spaced arms 33, 39, 40, and 41 (Fig. 7). Frame 37 carries arms opposite these arms, arm 71 being opposite arm 41; and arm 72 being opposite arm 38. These arms serve to support rods 42 upon which rolls 43 of sensitized paper may be mounted.

As before, rods 42 are mounted in a universal manner in the left-hand frame 37. For this purpose, the rod 42, as shown in Fig. 8, is provided with a ball end 44. It is universally movable in a socket formed by the arm 71 and a socket member 45.

The right-hand ends of all of the rods are removably mounted in the right-hand frame 36.

Thus, one of the arms 41 of the frame is shown in Fig. 8. It is received in a slot 47 leading obliquely from the arm 41. The rod 42 is retained in operative position by the aid of a pivoted latch 46, the end of which projects into the

slot 47. A compression spring 48 urges the latch to latching position. The latch 46, however, may be manually rotated out of the path of the rod 42. Then the rod may be moved transversely for removal and replacement of rolls.

The latch 46 is supported upon a bracket 49 that is appropriately joined to the arm 39. Each of the other arms 40, 41 and 38 are similarly equipped with latches 46.

10 For the position indicated in Fig. 7, the left-hand roll 43 is active and supplying sensitized paper 50 to the printing machine. In order to bring any one of the other rolls into active position, use is made of a hand wheel 51 (Figs. 5 and 15 6). This hand wheel is mounted on the shaft 35. It is arranged to be latched in any one of the four positions, bringing the rolls 43 successively into operative relation with the machine. For this purpose, use is made of a latch illustrated most 20 clearly in Fig. 9. This latch is arranged to hold any one of four spokes 52 of the wheel 51. These four spokes are equi-angularly spaced and correspond to an active position of the left-hand roll.

25 The latch structure is mounted on a base 53 that projects laterally from the bracket 33. It is provided with a pair of hook members 54 and 55. Each of these members is urged to engaging position, as by compression springs 56 and 57. They are pivoted by aid of a bearing standard 58, joined to the base 53.

30 Hook member 54 has a sloping face 59 that is contacted by the spoke 52 to permit the spoke to pass beyond the hook member. It is urged into contact with the abrupt face 60 of the other hook member 55. This hook member, however, may be released by the aid of a handle 61 to free the spoke and to permit rotation of the wheel 51 when desired.

35 40 In order to provide a light-proof enclosure for all rolls except the one which is in use, a sheet metal cylindrical casing 62 is provided. This cylindrical casing is supported by aid of a sheet metal bracket 63 on the vertical wall 64 (Fig. 5) formed on the printing machine. The casing has ends 65 and 66 through which the shaft 35 passes. It also has an opening at the left-hand side, as viewed in Fig. 5, which is adapted to be closed by an arcuate cover member 67 having a handle 68. When the machine is not in use, this cover member 67 may be rotated to close the casing entirely. The paper 50 is led through the opening in the casing 62.

45 50 Further to ensure against entry of light, resilient light seals 69 such as of flexible rubber, are provided. These light seals have free edges urged into resilient contact with the inner cylindrical surface of casing 62, as well as with the surfaces of the ends 65 and 67. Preferably, these seals may be mounted on sheet metal members 70 carried by the frame members 36 and 37. The inner ends of the seals 69, as shown most clearly in Fig. 7, are also in sealing contact with the hubs formed on the frame members 36 and 37 and on the ends 65 and 66.

55 60 In order to retard free movement of the paper from the rolls, springs may be mounted to exert a slight friction on the roll periphery. One such spring 74 is shown in Fig. 6. It is in the form of a bowed leaf spring having a central friction shoe 75 engaging the inner portion of the periphery of the corresponding roll 43.

The inventor claims:

65 70 1. In a roll supporting structure: a frame; means for pivotally mounting the frame about an

axis; a plurality of rods supported by said frame upon which rolls are to be supported, and having their axes arranged parallel to the frame axis and angularly spaced thereabout; means for releasably holding the frame in any of a plurality of angular positions about the frame axis; means providing a pivotal mounting on said frame for one end of each rod; means for detachably holding the other end of each rod in roll supporting position, including means forming a recess having a wall inclined with respect to the normal position of the rod axis for cooperating with said other end of the rod to permit the rod to be swung about its pivotal mounting out of its normal position, said wall having an aperture for the reception of said other end of the rod when said other rod end is moved to operative position; and a spring urging the rod into the aperture.

2. In a roll supporting structure: a frame; means for pivotally mounting the frame about an axis; a plurality of rods supported by said frame upon which rolls are to be supported, and having their axes arranged parallel to the frame axis and angularly spaced thereabout; and a pair of latches for releasably holding said frame in any of a plurality of angular positions about the frame axis, a part of the frame being adapted to be confined between the latches, one of said latches having means for manually releasing it; and the other having an inclined face adapted to be engaged by the frame to urge the latch out of the path of the frame until the frame approaches the other latch.

3. In a supporting structure for rolls of photographically sensitized material: a stationary cylindrical housing having an opening through which material from a roll may pass; a pivotally mounted frame in the housing; a plurality of means carried by the frame for supporting a plurality of rolls; means external of the housing for angularly adjusting the frame to cause any of the rolls carried thereby to assume a cooperative position with the opening; and light sealing partitions carried by the frame and extending between the roll carrying means, and slidably contacting with the inner surface of the housing.

4. In a supporting structure for rolls of photographically sensitized material: a stationary cylindrical housing having an opening through which material from a roll may pass; a frame pivoted about the axis of the housing and located therein; a plurality of roll supporting rods carried by the frame, having axes parallel to the housing axis; means external of the housing for angularly adjusting the frame to cause any of the rods to be in cooperative position with the opening; and partitions between the rods and carried by the frame, said partitions having resilient light sealing edges slidable along the ends and the cylindrical surface of the stationary housing.

5. In a supporting structure for rolls of photographically sensitized material: a cylindrical housing having an opening through which material from a roll may pass; a cover for the opening; a frame having a shaft pivotally mounted in the ends of the housing and coaxially with the housing; said frame having a plurality of arms adjacent each end of the housing; roll supporting rods carried by the arms; a wheel mounted on the shaft externally of the housing for angularly adjusting the frame, said wheel having spokes; and a releasable latch engageable with one of said spokes for holding the frame in angularly adjusted position.

6. In a supporting structure for rolls of photographically sensitized material: a stationary cylindrical housing having an opening through which material from a roll may pass; a cover for the opening; a frame having a shaft pivotally mounted in the ends of the housing and coaxially with the housing; said frame having a plurality of arms adjacent each end of the housing; roll supporting rods carried by the arms; a wheel mounted on the shaft externally of the housing for angularly adjusting the frame; a releasable latch cooperating with the wheel for holding the frame in angularly adjusted position; and partitions carried by the frame, and extending between the rods, said partitions having resilient light sealing edges slidably engaging the ends and the cylindrical surface of the housing.

7. In a roll supporting structure: a rod; a support for one end of the rod, having provisions for permitting angular movement of the rod about the support; means forming a recess having a wall inclined with respect to the normal position of the rod axis, and cooperating with the other end of the rod to permit the rod to be moved out of its normal position, said wall having an aperture for the reception of said other end when the said other end is moved to operative position; and a spring urging the rod into the aperture.

8. In a roll supporting structure: a frame; means for pivotally mounting the frame about an axis; a plurality of rods supported by said frame upon which rolls are to be supported, and having their axes arranged parallel to the frame axis and angularly spaced thereabout; means for releasably holding the frame in any of a plurality of angular positions about the frame axis; means providing a universal mounting in said frame for one end of each rod; and means for detachably holding the other end of each rod in roll supporting position, including a slot in said frame disposed transversely of the rod axis; and spring means engageable with said rod and movable lengthwise of the rod in a plane in which said axis lies for holding said rod in said frame in roll supporting position with its axis parallel to the frame axis.

9. In a roll supporting structure: a frame comprising axially spaced arms extending on opposite sides of the frame axis; means for pivotally mounting the frame about its axis; a plurality of rods supported by said arms and upon which rolls are to be supported, and having their axes arranged parallel to the frame axis and angularly spaced thereabout; and a pair of latches for releasably holding said frame in any one of a plurality of angular positions about the frame axis; means urging said latches toward each other to cause said latches to embrace one of said arms; one of said latches having means for manually releasing it from said one arm; and the other of said latches having an inclined face adapted to be engaged by said arm to urge said other latch out of the path of the arm until the arm is disposed between said latches to be confined thereby.

10. In a roll supporting structure: a frame; means pivotally mounting the frame about an axis; a plurality of rods supported by said frame upon which rolls are to be supported, and having their axes arranged parallel to the frame axis and angularly spaced thereabout; means for releasably holding the frame in any of a plurality of angular positions about the frame axis; means providing a mounting on said frame for one end

7
of each rod; means for detachably holding said other end of each rod in roll supporting position, including means forming an aperture for receiving said other end of the rod, and a spring encircling said rod at said one end and engaging said frame to urge the rod into the aperture.

11. In a roll supporting structure: a frame; means pivotally mounting the frame about an axis; a plurality of rods supported by said frame upon which rolls are to be supported, and having their axes arranged parallel to the frame axis and angularly spaced thereabout; means for releasably holding the frame in any of a plurality of angular positions about the frame axis; means providing a mounting on said frame for one end of each rod; means for detachably holding said other end of each rod in roll supporting position, including means forming an aperture for receiving said other end of the rod, a collar on the rod at said one end, and a spring bearing upon said collar and frame and urging the rod into the aperture.

12. In a supporting structure for rolls of photographically sensitized materials: a stationary housing having spaced end portions and an intermediate portion extending between said end portions, said intermediate portion having an opening through which material from a roll may pass; a pivotally mounted frame in the housing; a plurality of means carried by the frame for supporting a plurality of rolls; means external of the housing for angularly adjusting the frame to cause any of the rolls carried thereby to assume a cooperative position with the opening; and light sealing partitions carried by the frame and extending generally radially of the pivotal axis of said frame between the roll carrying means, said partitions slidably contacting said end and intermediate portions of said housing.

13. In a supporting structure for rolls of photographically sensitized material: a stationary housing having spaced end portions and an intermediate portion extending between said end portions, said intermediate portion having an opening through which material from a roll may pass; a pivotally mounted frame in the housing; a plurality of means carried by the frame for supporting a plurality of rolls; means external of the housing for angularly adjusting the frame to cause any of the rolls carried thereby to assume a cooperative position with the opening; and light sealing partitions carried by the frame and extending generally radially of the pivotal axis of said frame between the roll carrying means, said partitions having flexible means thereon in slidably sealing contact with said end and intermediate portions of said housing.
